UNITED STATES PATENT OFFICE.

JOSEPH J. SMITH, OF NEW YORK, N. Y.

HUMIDIFIER.

No. 872,384.

Specification of Letters Patent.

Patented Dec. 3, 1907.

Application filed May 7, 1903. Serial No. 155,988.

To all whom it may concern:

Be it known that I, JOSEPH J. SMITH, a citizen of the United States, residing at New York city, county and State of New York, 5 have invented certain new and useful Improvements in Humidifiers, of which the following specification and accompanying drawing set forth that form of my invention which I now regard the best of the various 10 forms in which the principle of the invention may be embodied.

Figure 1 of the drawing is a vertical section of my apparatus viewed from the front, Fig. 2 is a section transverse to that of Fig. 15 1, and Fig. 3 is a detail.

My invention relates to an apparatus for humidifying the atmosphere in living apartments by means of a contact of all parts of the air in the apartment with a series of absorbent sheets over which water is thoroughly distributed, the object being to cause the said air to evaporate and carry off the water to the required degree, and to extend this evaporation to as large a part of the air as 20 possible, in distinction from the injection of water into the air at local points where it may be carried off without becoming evaporated and so deposited upon surfaces in the apartment.

30 In an application for patent No. 104,266, filed by me on April 23rd, 1902, I show and describe an apparatus by which the air in an apartment may be properly humidified by passing it repeatedly over a series of sheets 35 stretched within a casing and provided with means by which water may be uniformly distributed over them.

40 My present invention relates to certain improvements upon the machine of the said application and serves to simplify and render more effective and reliable the humidifier shown generically therein.

Referring to the drawing, A represents an upright casing resembling in size and appearance a tall clock, having about the same weight and similarly portable and self contained, so that it may be conveniently placed in any desired apartment and removed therefrom with equal facility. Within this casing there are stretched a series of vertical sheets B B made of absorbent textile fabric like heavy cheese-cloth, which will readily absorb and retain moisture. At the upper ends these sheets are respectively looped 50 over a series of horizontal tubes C connected to a distributor D. These tubes C are slit or

perforated, as, for example, on their under side (see Fig. 3), the slits or perforations being sufficiently above the level of the water in the distributing tank D, to insure a distribution of the water by means of the tank, and a simultaneous outflow at all of the perforations whenever the level of the water in the tank is raised by the pump. At the lower ends the absorbent sheets B B are 55 looped over rods E E which are held respectively in notches cut on the under side of retaining pieces F F attached to the opposite sides of the interior portion of the casing.

In the enlarged upper portion of the casing there is contained a blower G having its axis horizontal and operated by an electric motor H secured to and upheld by the casing of the blower and having its commutator end projecting through the front of the casing so that the commutator can be readily inspected and the brushes renewed without opening the casing. This arrangement avoids the use of such a shield or deflector as is shown in my former application to protect the motor and blower from the falling water from the sheets. The shaft of the blower stands transversely to the planes in which the vertical absorbent sheets B B are situated. This allows the incoming air blast 85 taken in through the open top of the casing to be split up and divided by the sheets into a number of streams which pass respectively through the parallel passages into which the interior of the casing is divided by the sheets. 90 The flow of the air is downward, which permits of the incoming air being taken from the upper part of the room, where the temperature is higher and its absorbent capacity greater. The air is delivered again into the 95 apartment from the lower end of the casing, which insures its being delivered into the portions of the apartment occupied by the persons therein and by other objects which require a moist atmosphere. The downward 100 draft causes the air to collect in the lower portion of the casing depositing there any unevaporated water, whence it finds its exit into the apartment by the openings J J in the removable front K. In the bottom of the 105 casing is a tank L, serving both as the source of supply and as a drip tank for receiving any excess of moisture flowing from the sheets B B. This arrangement also allows the water in the air to be blown into the tank 110 which is in line with the blast. Directly over the tank is the pump P supported from

the rear wall of the casing by the bracket Q. The intake pipe R of the pump P communicates with the tank and the outflow pipe S leads up to the distributor D. The pump is 5 of a reciprocating type, serving to deliver the water to the distributor D by a series of impulses, each of which causes a rise in the level of the water in the distributor D and produces a simultaneous flow into 10 each of the perforated tubes C. The pump is operated by a long connecting rod f extending down between two of the absorbent sheets and connected at its upper end to a crank shaft journaled in standard V and 15 driven from the motor by a belt which surrounds the grooved wheel W of the crank shaft and the small pulley X on the motor shaft inside of the bearing Y of the said shaft. By this arrangement the pump supports 20 the column of water in the outflow pipe S from below instead of relying on suction from above, while at the same time the belt, required for the drive from the small, high-speed motor, is contained only in the 25 upper part of the casing above the wet sheets so as to be unaffected thereby, while the connecting rod, extending down through the sheets to the pump, is unaffected by the moisture. The pumping apparatus thus 30 described runs silently, with a minute amount of power and is not disarranged by the stretching and slipping of belts exposed to moisture.

The apparatus described constitutes an extremely simple and effective device which is portable and self-contained and by means of which the moisture is thoroughly and uniformly distributed over the large surface formed by the multiplicity of passages intervening 35 between the sheets, and the air is thoroughly sub-divided within the apparatus, so as to be all exposed to the evaporating process. Moreover, the air of the apartment is repeatedly passed through the apparatus, it being the practice to provide that the entire atmospheric contents of the room shall go through the humidifier every hour. The operation is further facilitated by the separation between the inlet and outlet openings 40 in the casing which provides for an intake of the air at a point remote from the outflow. This also insures a thorough agitation and mingling of the air throughout the entire apartment, as well as the passage of 45 the whole of the air through the apparatus.

What I claim as new and desire to secure by Letters Patent is:

1. A humidifying apparatus for apartments, comprising a vertical casing with 50 openings at opposite ends communicating with the apartment to be treated, to receive air from the upper part of said apartment and discharge the air into the lower part of the same, a series of absorbent sheets dividing 55 the casing into a series of longitudinal

side by side passages between the said inlet and outlet openings, a drip tank below the said sheets, means for distributing water to the upper ends of said sheets, and a blower for delivering air currents in a downward direction from the inlet to the outlet, through 70 the passages formed by the said sheets.

2. A humidifying apparatus for apartments, comprising a vertical casing with inlet and outlet openings at its opposite ends 75 respectively, both openings communicating with the apartment to be treated, to receive air from the upper part of said apartment and discharge the air into the lower part of the same, a series of absorbent sheets dividing 80 the casing into a series of longitudinal side by side passages between said inlet and outlet openings, a tank in the lower part of the casing below the said sheets to receive the drip therefrom, means for distributing 85 water to the upper ends of said sheets, and a blower located in the casing above said sheets and delivering air currents in a downward direction from the inlet to the outlet openings in the casing. 90

3. A humidifying apparatus for apartments, comprising an upright casing having an inlet opening at its upper end and an outlet opening at its lower end, both openings 95 communicating with the apartment to be treated, whereby the incoming air may be taken from the upper part of the apartment, a series of absorbent sheets dividing the casing into a series of side by side passages between its inlet and outlet openings, means 100 for supporting the sheets and for distributing water to the upper ends of said sheets, and a blower producing a downward air current from the inlet opening, which current is subdivided into the side by side passages and delivered into the apartment from the outlet opening in the lower part of the casing. 105

4. A humidifying apparatus for apartments, comprising a casing having its inlet and outlet openings both communicating with the apartment to be treated, a series of absorbent sheets dividing the casing into a series of side by side passages between its inlet and outlet openings, a combined drip and supply tank in the lower part of the 115 casing, a blower and motor in the upper part of the casing above said sheets, a pump in the lower part of the casing communicating with the said tank on one side and on the other side with the upper ends of the sheets, and operating-connections for the pump extending from the motor at one end of the casing to the pump at the other end. 120

5. A humidifying apparatus for apartments, comprising a casing having inlet and 125 outlet openings at its opposite ends communicating with the apartment to be treated, a series of absorbent sheets therein, a supply tank at the lower end of the casing, a pump also at the lower end of the casing, a motor 130

- and blower at the upper end of the casing, and a connecting rod operated by the motor and extending downward to the pump at the lower end of the casing.
- 5 6. A humidifying apparatus for apartments, comprising an upright casing with inlet and outlet openings at its opposite ends, both openings communicating with the apartment to be treated, a series of sheets 10 dividing the intermediate portion of the casing into side by side passages, a motor and blower contained in the upper part of the casing above the said sheets, a tank and pump in the lower end of the casing, the 15 intake side of the pump communicating with the said tank and its outflow side communicating with a distributor at the upper ends of said sheets, and operating devices for the pump extending from the 20 upper to the lower end of the casing and having a driving connection with the motor.
7. A humidifying apparatus for apartments, comprising an upright casing with inlet and outlet openings at its opposite 25 ends communicating with the apartment to be treated, a series of absorbent sheets dividing the casing between the said inlet and outlet openings into side by side passages, a

drip-tank below the said sheets, a blower mounted above the sheets, an operating 30 motor mounted on the blower casing, a pump in the lower part of the apparatus having its outflow pipe communicating with the upper end of the said sheets, and operating connections for the pump driven from 35 the motor shaft through an intermediate shaft and communicating with the pump at the lower part of the casing.

8. A portable humidifying apparatus for apartments comprising a vertical casing 40 opening at both ends into the apartment to be treated, a series of absorbent sheets dividing the intermediate part of the casing between the said openings into side by side 45 passages, a drip-tank below the said sheets, motor-supplying and distributing devices for said sheets and a blower directing an air-current downward along said sheets toward said tank.

In witness whereof I have hereunto set 50 my name, before two subscribing witnesses, this 21st day of April 1903.

JOS. J. SMITH.
